LINE BALANCE CONVERTER

George H. Brown, Princeton, N. J., assignor to
Radio Corporation of America, a corporation
of Delaware

Application January 17, 1945, Serial No. 573,217

5 Claims. (Cl. 178—44)

1

This invention relates to line balance convertor systems, for use in transferring radio frequency power between balanced and unbalanced circuits or lines. The term "balanced" is used to designate a circuit or line including two conductors which are electrically symmetrical with respect to a neutral or ground point. The term "unbalanced" refers to a line or circuit which is electrically unsymmetrical with respect to its ground point. For example, a concentric transmission line with a single inner conductor and a grounded outer conductor is unbalanced. A dipole radiator, comprising two elements extending in opposite directions from a neutral point and fed at that point so that current is flowing into one element while an equal current flows out of the other, is balanced. It is frequently necessary to couple an unbalanced line or source to a balanced load, or vice versa, and line balance convertors are used for this purpose. Typical prior art line balance convertors are described on page 855 of Radio Engineering Handbook, F. E. Terman, published by McGraw Hill Book Company, 1943.

It is the principal object of the present invention to provide improved line balance convertor systems capable of efficient power transfer throughout a wide band of radio frequencies.

Another object of the invention is to provide line balance convertor systems which maintain accurate balance, independently of frequency.

A further object of this invention is to provide line balance convertors which are structurally simple, rugged, and easily designed to fulfill broad-band performance requirements.

The invention will be described with reference to the accompanying drawing, of which

Figures 1 and 2 are schematic diagrams of typical prior art line balance convertors.

Figure 3 is a schematic diagram of a line bal-

Figure 4 is a modification of the structure of

Referring to Figure 1, one well-known type of

Referring to Figure 1, one well-known type of line balance convertor includes a cylindrical conductive sleeve 1 surrounding a quarter wavelength section 3 at the end of a coaxial transmission line 5. The line 5 comprises the unsymmetrical or unbalanced circuit of the convertor. The sleeve 1 is connected to the line section 3 by a conductive disc 7. A pair of transmission lines 9 and 11 are connected to the inner and outer conductors respectively of the line

section 3. The upper end of the sleeve 1 is closed by a disc 8. The operation of the system of Figure 1 is as follows: Assume that the line 5 is fed by a radio frequency source, E, and that equal loads, Z and Z', are connected to the lines 9 and 11. When current is flowing upward on the inner conductor of the line 3, an equal current must flow downward on the inner surface of the outer conductor of the line 3. Therefore, the current flows out on the inner conductor of 9. The return current, on the inner surface of the outer conductor of line 9 flows across the disc 8 to the inner surface of the outer conductor of line 11, through the load Z' and back to the outer conductor of line 3. The current cannot flow into the high impedance of the stub 1, 3 and must go back down the inner surface of the outer conductor of line 3. Thus the same current flows through both loads Z and Z', but in opposite directions, i. e. toward ground in one load while away from ground in the other. The loads Z and Z' are effectively in series with each other across the input.

25 The outer conductor of the line 3 cooperates with the sleeve 1 to act as a short-circuited quarter wave line connected across the line 11. At resonant frequency, the impedance presented by this line across the line 11 is substantially infinite, and does not affect the flow of current to the load Z'. At frequencies other than resonance, the short-circuited quarter wave section presents a relatively low impedance across the line 11 but not across the line 9. The greater the difference between actual frequency and the resonant frequency, the greater will be the difference between the currents flowing to the loads Z and Z'.

30 In accordance with prior art practice, the effect of the short-circuited line 1, 3 is balanced by means of a second short-circuited quarter wave line section 1', 3' shunted across the line 9 as illustrated in Figure 2. In the system of Figure 2, the lines 9 and 11 are shunted by substantially identical quarter wave stubs, and although the reactances of the stubs vary with frequency, the same amount of reactance is shunted across each of the balanced lines at all frequencies, so that the balanced line currents are equal, independently of frequency. However, if the frequency of operation is varied widely from the resonant frequency, the reactances of the short-circuited stubs will vary accordingly, seriously affecting the efficiency of the power transfer through the convertor circuit. The band width over which the convertor will operate efficiently depends upon

the ratio of the characteristic impedance of the stubs to the line impedance. These variations in reactance may be compensated to some extent by means of further short-circuited stubs connected to points on the lines 9 and 11 one-quarter wavelength distant from the stubs 1, 3, and 1', 3'. A compensated line balance convertor of this type will operate efficiently over a fairly wide frequency band, but has the disadvantage of complexity.

In accordance with the present invention, it is proposed to shunt the necessary reactance elements across the unbalanced line circuit rather than one of the balanced line circuits. Referring to Figure 3, the inner conductors of the balanced lines 9 and 11 are connected directly together, and the sleeve 1 surrounds the final quarter wavelength section 13 of the line 9. The end of the outer conductor of the unbalanced line 5 is connected to the sleeve 1 and the inner conductor of the line 5 is connected to the end of the outer conductor of the line 9. The reactance of the short-circuited stub 1, 13 is shunted across the line 5, and the balanced lines 9 and 11 are effectively in series with each other across the line 5.

Current flowing upward on the inner conductor of the line 5 cannot flow down the outside of the outer conductor of the line 9 owing to the high impedance presented by the short-circuited section 1, 13, and therefore, must flow down the inside of the outer conductor of the line 9 to ground. This current on the inside of the outer conductor of the line 9 induces an equal and opposite current on the inner conductor of the line. This current flows up through the load Z through the lines 9 and 11 and down through the load Z'. The currents through the loads Z and Z' will be equal at all frequencies because the reactance of the stub 1, 13 is across both loads. Thus the system of Figure 3 will provide operation which is equivalent to the system of Figure 2, without requiring the addition of the compensating stub.

As in the system of Figure 2, the variation of the convertor reactance with frequency will cause inefficient operation at frequencies differing widely from resonance. However, the characteristic impedance of the stub must be twice as great as that of Figure 2, for operation over a given band width, because the stub is across both balanced lines. These variations may be partially compensated by introducing a similarly varying reactance across line 5 at a point one-quarter wavelength from the convertor, as mentioned above in connection with the system of Figure 2. It is preferable, however, to compensate the reactance of the stub line by the means disclosed and claimed in copending U. S. application Ser. No. 551,247 filed August 25, 1944, by G. H. Brown and entitled Reactance Compensation, now Patent No. 2,419,985, issued May 6, 1947.

Referring to Figure 4, the half wavelength line section 15 is connected between the end of the unbalanced line 5 and the convertor. The end of the line 5 is shunted by a short-circuited quarter wave stub 17, which is designed to have a characteristic impedance equal to that of the stub 1, 13. The resultant impedance presented by the lines 9 and 11 across the convertor end of the half wave section 15 are made equal to the impedance presented to the other end of the line section 15 by the unbalanced line 5. This may be done by introducing suitable impedance trans-

formation circuits in the lines 9 and 11 or in the line 5, or by designing the balanced circuits to operate at an impedance level which is one-half that of the unbalanced circuit. Denoting the impedance level of the unbalanced circuit as Z_0 , the surge impedances of the stubs 1, 13 and 17 as Z_s and the surge impedance of the half wave line section 15 as Z_c , the value of Z_c should be adjusted with relation to the impedance Z_s and Z_0 so that the quantity

$$\frac{Z_c}{Z_0}$$

has a value within the range of 90 to 100 percent of that of the quantity

$$\frac{1 + \sqrt{1 + 4 \left(\frac{Z_s}{Z_0} \right)^2}}{2 \frac{Z_s}{Z_0}}$$

If the system of Figure 4 is designed to fulfill the above relationship, efficient line balance conversion will be obtained throughout a very broad band of operating frequencies.

The invention has been described as an improved line balance convertor system wherein accurate balance is obtainable independently of frequency by means of a relatively simple structure. This structure differs from the conventional line balance convertor systems in that the reactance elements are shunted across the unbalanced terminals, rather than across only one of the balanced lines, so that variation of the reactance of frequency does not effect the balance.

I claim as my invention:

1. A line balance convertor comprising a coaxial line section one-quarter wavelength long, the ends of the inner conductor of said section constituting balanced line terminals, a conductive sleeve surrounding said line section and connected at one end to the outer conductor of said section, a half wavelength coaxial line section with one end of its outer conductor connected to said sleeve and its inner conductor connected to the free end of the outer conductor of said quarter wavelength line section, the other ends of the inner and outer conductors of said half wavelength line constituting unbalanced line terminals, and a short-circuited quarter wavelength line section connected across said unbalanced terminals.

2. The invention as set forth in claim 1 wherein in said last-mentioned quarter wavelength line section has a surge impedance equal to the surge impedance between the outer conductor of said first-mentioned quarter wave line and said conductive sleeve.

3. The invention as set forth in claim 1 wherein in said last-mentioned quarter wavelength line section has a surge impedance equal to the surge impedance between the outer conductor of said first-mentioned quarter wave line and said conductive sleeve, and said half wavelength line section has a surge impedance which is higher than the impedances of the lines to be connected to the convertor.

4. The invention as set forth in claim 1 wherein in said last-mentioned quarter wavelength line section has a surge impedance Z_s equal to that between the outer conductor of said first-mentioned quarter wavelength line section and said conductive sleeve, and said half wavelength line section has a surge impedance Z_c , the impedances

Z_s and Z_c being related to the terminal impedance Z_0 of the convertor as follows:

$$\frac{Z_c}{Z_0} = \frac{1 + \sqrt{1 + 4 \left(\frac{Z_s}{Z_0} \right)^2}}{2 \frac{Z_s}{Z_0}}$$

5

5. The invention as set forth in claim 1 wherein said last-mentioned quarter wavelength line section has a surge impedance Z_s equal to that between the outer conductor of said first-mentioned quarter wavelength line section and said conductive sleeve, and said half wavelength line section has a surge impedance Z_c , the impedances Z_s and Z_c being related to the terminal impedance Z_0 of the convertor so that the quantity

$$\frac{Z_c}{Z_0}$$

has a value within the range of 90 to 100 percent of that of the quantity:

$$\frac{1 + \sqrt{1 + 4 \left(\frac{Z_s}{Z_0} \right)^2}}{2 \frac{Z_s}{Z_0}}$$
